BOBBIN

Conrad W. Geier and Asher L. Joslin,
Robbins, N. C.

Application October 4, 1946, Serial No. 701,384

3 Claims. (Cl. 242—120)

1

This invention relates to a bobbin, and more especially to a bobbin having a base portion, a cylindrical portion, and a yarn receiving portion, the base portion having rings therearound whereby it can be inserted into a shuttle spring for holding the bobbin in position, and said bobbin having between the base portion and the yarn receiving portion a cylindrical portion, which has the same diameter as the spaced rings around the butt or base of the bobbin, said bobbin also having a metallic bushing in its butt portion whereby the butt portion and the cylindrical portion combined are heavier than the yarn receiving portion of the bobbin, together with the yarn thereon, so that the bobbin when lying on a flat surface will have its butt portion heavy enough to sustain the weight of the yarn without the yarn touching an adjacent surface and chafing as a result of rubbing.

Also, the bobbin, when filled with yarn, and placed in a loom, such as a Crompton and Knowles box loom, will cause the butt and cylindrical portions to rest against each other and thus prevent the yarn on adjacent bobbins from touching, thus protecting the yarn. The bobbin, also, is adapted to be used with a transfer arm, which has one point which engages the rings for transferring the bobbin, and also has an extension which instead of engaging the yarn during the transfer operation and damaging the same, engages the cylindrical intermediate portion of the bobbin, instead of the yarn, thus preventing the yarn from being damaged during a transfer operation.

In a magazine loom, such as a Crompton and Knowles, S-5 type of loom, where this bobbin is best adapted to be used, this type of loom has a magazine and the filling bobbins are held in position by two almost vertical U-shaped guides, one at the butt and the other at the end of the bobbin. The first bobbin stops at the bottom of the guide, being held there by giveaway or releasable stops. The next bobbin rests on top of the first bobbin, and so on, and there are several bobbins placed on upon the other, and in the old type of bobbin, the yarn on each bobbin is in contact with the yarn on the bobbin both above and below the same. At time of transfer, a transfer arm strikes the bottom bobbin and forces it through the releasable stop and into the shuttle. This transfer arm strikes the bobbin in two places, one place at the butt, and the other about half-way to the tip of the yarn, striking the yarn in the old-type bobbin.

After the bottom bobbin is transferred, the bobbins in the magazine all slide down the guides by

2

gravity so that the previous second bobbin becomes the first one, and is ready for the next transfer. All other bobbins slide down to the position of the bobbin previously just below it.

During this transfer operation, the section of the transfer arm striking the yarn has an extended side which holds the second bobbin from sliding down the guide until the transfer arm is back in its inoperative position. Consequently, the yarn of the transferred bobbin is struck by the face of the transfer arm, and the yarn on the second bobbin is rubbed by the side of the transfer arm on each transfer when the old type bobbin and the old type transfer arms are used.

This section of the transfer arm which contacts the yarn also guides the tip sections of the bobbin to their proper position in the shuttle during transfer, the position of the butt of the bobbin being governed by the butt section of the transfer arm.

When the bobbin is not fully wound with yarn, the wound diameter of the yarn on the bobbin is, of course, smaller. This results in the tip of the bobbin not being forced to its proper position during the transfer. This condition, in turn, because the bobbin is not being properly placed in the shuttle, is liable to cause breakage of loom parts and failure of the shuttle to thread up properly. Most of these occur in the pick immediately following transfer.

The new type of bobbin enables a satisfactory, automatic transfer, with a partly filled bobbin for the reason that a section of the transfer arm, which would ordinarily strike the yarn, is made shorter and is caused to strike the enlarged cylindrical section between the yarn receiving portion of the bobbin and the butt portion of the bobbin. Therefore, the amount of yarn on the bobbin has no effect on the guiding of the bobbin during transfer, as it ordinarily does in the types of bobbins heretofore used.

This new type of bobbin prevents damage to the yarn for the reason that the bobbins will be resting against each other in the magazines, and having the cylindrical portions of each bobbin in contact with each other, rather than the yarn, as it does in the old type of bobbin heretofore used. The weighted bushing at the butt section of this improved bobbin will over-balance the weight of the yarn on the bobbin, and thus assuring that no contact between the yarns of adjacent bobbins will take place.

By the use of the new type bobbin and a shorter extension on the transfer arm, damage to yarn during transfer is eliminated for the reason that

all contact of the yarn by the transfer arm is eliminated with this new type of bobbin. The arm contacts rather the butt portion of the bobbin as heretofore, and cylindrical portion disposed between the butt portion and the yarn receiving portion of the bobbin.

By eliminating the part currently played by the yarn and properly guiding the bobbin to a complete transfer, partially filled bobbins may be transferred successfully, which result has not been successfully attained with the old type of bobbin heretofore used.

The use of this improved bobbin reduces breakages of the yarn and breakages of loom parts, as all parts of the bobbin used to guide the bobbin to a transfer, namely, the butt section of the enlarged mid section, and the tip section, will remain the same, and not be affected by the amount of yarn on the bobbin, as it is with the heretofore type of bobbin used.

By using this improved bobbin, the threading action of the shuttle is improved because of the uniform control of the bobbin during transfer, regardless of the amount of yarn on the bobbin, which control varies according to the amount of yarn on the bobbin with the old type of bobbin heretofore used.

It is therefore an object of this invention to provide an improved bobbin having a butt portion with spaced rings therearound, and having a yarn receiving portion, and having a cylindrical portion, disposed between the butt portion and the yarn receiving portion, which cylindrical portion has a diameter greater than the diameter of the yarn wound on the yarn receiving portion of the bobbin; and which cylindrical portion is of substantially the same diameter as the rings on the butt portion of the bobbin; and said butt portion of the bobbin having disposed therein a hollow metallic bushing, which not only increases the life of the bobbin, but which also gives the necessary added weight thereto, so that the point of balance of the bobbin, when it is filled with yarn, is disposed at a point along the cylindrical portion, so that this cylindrical portion and the butt portion will outweigh the other portion of the bobbin and the yarn thereon, and thus prevent the bobbin from tilting and allowing its yarn to chafe against an adjacent object as the butt portion of the bobbin and cylindrical portion support the entire weight of the yarn without the bobbin tilting in any manner to chafe the yarn.

Some of the objects of the invention having been stated, other objects will appear as the description proceeds when taken in connection with the accompanying drawings, in which

Figure 1 is an elevation of the bobbin lying on a supporting surface;

Figure 2 is a longitudinal, sectional view through the bobbin, and taken along the line 2—2 in Figure 1;

Figure 3 is a cross-sectional view, taken along the line 3—3 in Figure 1;

Figure 4 is a cross-sectional view, taken along the line 4—4 in Figure 1;

Figure 5 is a sectional view taken along the line 5—5 in Figure 1.

Referring more specifically to the drawings, the numerical 10 indicates the base portion of the bobbin, which has three spaced rings, 11, 12, and 13, clamped therearound in a conventional manner, said rings usually being divided as at 14, and slightly imbedded in the wooden base portion 10. The bobbin has a cylindrical bore in its base por-

tion, in which a metallic bushing 15 is secured by a pressed fit and the like, and this bushing being tubular in form and having a bore 16 extending therethrough, which merges with a bore 17, which, in turn, merges with a smaller bore 18, the bores 17 and 18 extending through the yarn receiving portion 20 of the bobbin.

Integral with the base portion 10 and of larger diameter than the base portion 10 is a cylindrical portion 22, which has a diameter substantially the same as the diameter of the spaced rings 11, 12, and 13. The spaced rings 11, 12, and 13, of course, are conventional and are adapted to fit into suitable cavities in a spring clamp, disposed within a shuttle, for holding the bobbin in the shuttle during a weaving operation. The yarn is adapted to be wound on the portion 20 of the bobbin and is filled out usually to the dotted line indicated at 23. The diameter of the yarn on the portion 20 is slightly less than the diameter of the barrel or cylindrical portion 22.

The combined weight of the base portion and the bushing together with the barrel portion 15 is greater than the weight of the yarn receiving portion 20, together with the yarn thereon. The balance point of the bobbin filled with yarn is approximately at the point indicated by the arrow 24. The dotted line 25 indicates a flat supporting surface, and shows how the yarn on the bobbin 30 would not touch the supporting surface.

It is thus seen that when the bobbin is fully loaded with yarn that the weight of the butt portion of the bobbin will be sufficient to hold the yarn on the bobbin in the position shown in Figure 1, and prevent its tilting to where it would engage a support or an adjacent bobbin, thus to chafe and damage the yarn.

In the drawings and specification, there has been set forth a preferred embodiment of the invention, and although specific terms are employed, they are used in a generic and descriptive sense only, and not for purposes of limitation, the scope of the invention being defined in the claims.

We claim:

1. A bobbin comprising a yarn receiving portion and a cylindrical portion adjacent one end of the yarn receiving portion, and a butt portion having spaced rings therearound for fitting into the spring of a shuttle, the cylindrical portion being of greater diameter than the yarn wound onto the yarn receiving portion and being substantially of the same diameter as the rings on the butt of the bobbin, the weight of the butt of the bobbin and the cylindrical portion being greater than the yarn receiving portion together with the yarn thereon, so as to prevent the yarns on adjacent bobbins from chafing by contact with each other.

2. A bobbin having a base portion and a yarn receiving portion, said base portion comprising a cylindrical section of greater diameter than the yarn wound on the yarn receiving portion, and the base portion and the cylindrical portion being of greater weight than the yarn receiving portion together with the yarn wound thereon, so that when the bobbin with the yarn thereon rests upon a surface, the base portion and the cylindrical portion will support the yarn out of contact with said surface, the bobbin having a bore extending longitudinally therethrough, and a metallic cylindrical bushing mounted in the bore in the base of the bobbin to give added weight to the base portion of the bobbin.

3. A bobbin comprising a yarn receiving portion and a cylindrical portion adjacent one end of the

yarn receiving portion, and a base portion having spaced rings therearound for fitting into the spring of a shuttle, the cylindrical portion being of greater diameter than the yarn wound onto the yarn receiving portion and being substantially of the same diameter as the rings on the base of the bobbin, the weight of the base of the bobbin and the cylindrical portion being greater than the yarn receiving portion together with the yarn thereon, so as to support the yarn out of contact with a supporting surface, and to prevent the yarns on adjacent bobbins from chafing by contact with each other, the bobbin having a bore extending longitudinally therethrough, and a

cylindrical bushing mounted in the bore in the base of the bobbin to give added weight to the base portion of the bobbin.
